UNITED STATES PATENT OFFICE

150,230

DESIGN FOR A CAMERA

Frederick W. Hertzler, Detroit, Mich., assignor to Argus, Incorporated, Ann Arbor, Mich., a corporation of Michigan

Application March 28, 1947, Serial No. 138,010

Term of patent 14 years

(Cl. D61—1)

To all whom it may concern:

Be it known that I, Frederick W. Hertzler, a citizen of the United States, residing at Detroit, in the county of Wayne and State of Michigan, have invented a new, original, and ornamental Design for a Camera, of which the following is a specification, reference being had to the accompanying drawing, forming a part thereof.

side of the camera of Figures 1 through 3; and Figure 5 is a side elevational of the right side of the camera of Figures 1 through 4.

I claim:

The ornamental design for a camera, as shown.
FREDERICK W. HERTZLER.
